UNITED STATES PATENT OFFICE.

JOSEPH A. BARTOSZ, OF SALEM, OREGON.

DRAPER.

1,094,191.

Specification of Letters Patent. Patented Apr. 21, 1914.

Application filed March 21, 1913, Serial No. 755,855.

To all whom it may concern:

Be it known that I, JOSEPH A. BARTOSZ, a citizen of the United States, residing at Salem, in the county of Marion and State 5 of Oregon, have invented certain new and useful Improvements in Drapers, of which the following is a specification.

This invention relates to an improvement in drapers and has for its object to provide 10 an economical and efficient device for carrying the grain in selfbinders and the like. These and other objects are accomplished by means of the structure shown in the accompanying drawing, in which—

15 Figure 1 is a side elevation of the draper showing a slat in section. Fig. 2 is a similar view, showing a modified form of retaining element. Fig. 3 is an end elevation, showing a side view of a slat, of the form 20 shown in Fig. 2. Fig. 4 is a longitudinal sectional view of a slat, showing the position of the draper fabric in dotted lines. Fig. 5 is a bottom plan view.

Referring to the drawing in detail, 1 represents the fabric of which the draper belt 25 is constructed, and 2 are cross slats disposed at suitable intervals along the body of the belt to engage the grain or other matter falling thereon. Lengthwise along the lower 30 face of the slat is formed a groove 5, into which the body of the fabric 1 is forced by the follower 6, which consists preferably of a rod or wire of suitable gage for the purpose, and which is of a sinuous form 35 from end to end, giving it a greater lateral dimension in one direction, so that when the wire is forced into the groove the raised portions will project sufficiently to take the weight of the draper upon the track over 40 which it moves.

Across the depressed portion of the wire at suitable intervals are secured staples 3, the body of which will lie beneath the surface of the raised portions, and the arms 45 extend through suitably formed apertures 3^a to the upper face, where a transverse bar 4 is secured thereon. In this manner the two lateral portions of the slat are firmly bound together, so that there will be no danger of 50 splitting along the line of the groove, which is a common trouble with the devices now in use. The groove being cut according to the

gage of wire used, will not permit the wire in this sinuous form to rotate, and the staples being secured over the depressed portions will not permit a longitudinal movement of the wire. Even if the wire should become broken, the pieces could not become dislodged, as some portion would be held by a staple, so as to effectually prevent objects 60 from entering between the body of the slat and the fabric.

In Fig. 2 is shown a slight modification in which a straight wire is used; and a rivet 7 is secured in the groove at each end of 65 the wire to prevent longitudinal movement thereof. A washer 9 holds the fabric in place, and upon the opposite end of the rivet is secured a cross bar 8 extending across the upper face of the slat, and each end is bent 70 to engage its respective lateral face thereof, thus serving to sustain the slat in the same manner that the staples and bar do in the form shown in Fig. 1.

Having described my invention what I 75 claim as new and desire to secure by Letters Patent, is—

1. A draper comprising a belt fabric, a slat, a groove formed along the lower face thereof receiving a fold of said fabric, a 80 sinuous wire fitted into the groove within said fold, the raised portions projecting slightly beyond the surface of the groove, and retaining elements secured at intervals over depressed portions of the wire. 85

2. A draper comprising a belt fabric, a slat, a groove formed along the lower face thereof receiving a fold of said fabric, a follower comprising a sinuous wire fitted into the groove within said fold, the raised portions projecting slightly beyond the surface of the groove, staples secured at intervals in recessed portions of the wire, lateral members thereof extending vertically through their respective sides of the slat, and a bar 90 fixed across the upper face of the slat upon the staple members. 95

In testimony whereof I affix my signature in presence of two witnesses.

JOSEPH A. BARTOSZ.
